DESIGN FOR A CONTAINER

David L. Temple, St. Petersburg, Fla.

Application April 25, 1942, Serial No. 106,709

Term of patent 14 years

To all whom it may concern:

Be it known that I, David L. Temple, a citizen of the United States of America, residing at St. Petersburg, in the county of Pinellas, State of Florida, have invented a new, original, and ornamental Design for a Container, of which the following is a specification, reference being made to the accompanying drawing, forming a part thereof.

Fig. 1 is a front view, in perspective, of a container, showing my new design.

Fig. 2 is a top plan view of the container.

The bottom of the container is perfectly flat.

I claim:

The ornamental design for a container, as shown and described.

DAVID L. TEMPLE.
